UNITED STATES PATENT OFFICE.

ARON JOHNSON, OF BROOKLYN, NEW YORK.

APPARATUS FOR APPLYING CLOSURES TO RECEPTACLES.

Application filed January 10, 1921. Serial No. 436,146.

To all whom it may concern:

Be it known that I, ARON JOHNSON, a citizen of the United States, and a resident of the borough of Brooklyn, in the county of 5 Kings, city and State of New York, have invented certain new and useful Improvements in Apparatus for Applying Closures to Receptacles, of which the following is a specification.

10 This invention relates to apparatus for applying crown closures to receptacles, such as bottles, supported on a rotatable table by means of reciprocable closure applying devices rotatable with the table and to co-operate with a cam to have closure applying movement imparted thereto, the closures being fed automatically from a hopper to the closure applying devices at a predetermined point in the rotatable or revoluble 15 movement thereof, and it is the primary object of the invention to improve the general construction of apparatus for this purpose to simplify and cheapen the cost of construction and to provide apparatus which is 20 highly efficient in operation.

In apparatus of this character to adapt the same for applying closures to receptacles of different sizes the apparatus is constructed to provide adjustment between the closure applying devices and a receptacle support, and it is a further object of the invention to provide a structure in which the receptacle supporting table is rotatably mounted in fixed position and the closure applying devices with the actuating means therefor, as well as the closure applying means, is constructed and arranged to have adjustment as an integral unit toward and away from the receptacle supporting table, driving means being provided therefor mounted in fixed position and having operative connection with the closure applying devices and closure feeding or supplying means adapted to permit of adjustment thereof relative to the table without uncoupling or breaking the operative connection with the driving means.

It is another object of the invention to provide an improved construction and arrangement of closure applying means.

It is a further object of the invention to provide improved means for feeding the closures to the closure applying devices.

It is another object of the invention to

provide improved driving means in apparatus of this character whereby the same may be operated at different speeds.

It is still another object of the invention to provide improved means for feeding the receptacles to the receptacle support and position the same on the table relative to the closure applying devices.

The receptacles, bottles, made of glass, to which the apparatus is adapted to apply the closures are invariably of different sizes or heights due to defects in manufacture and as the operating cam for moving the closure applying devices to closure applying position is arranged to impart a predetermined closure applying movement to such devices, and should a receptacle be of greater height than the space between the receptacle supporting table and said devices for which the latter is adjusted relative to the table a crushing force or pressure will be applied to such receptacle by the closure applying devices through the action of the cam thereon which the receptacle will be unable to resist with the result that it will be broken. To obviate this means are provided to permit of movement relative of one to the other and when a pressure greater than a predetermined force is applied to the closure applying devices to compensate for the inequality in the size of the receptacles.

It is another object of the invention to construct and arrange the actuating cam for the closure applying devices whereby the high or working portion of the cam portion of the cam may have slight movement relative to the body of the cam to permit of this compensating movement of the closure applying devices relative to a receptacle.

Other objects and advantages will herein-after appear.

In the drawings accompanying and forming a part of this specification Figure 1 is an elevational view, partly in section, of apparatus for applying closures to receptacles illustrating an embodiment of my invention.

Figure 2 is an enlarged elevational view, partly in section, of driving means for the apparatus.

Figure 3 is a plan view of the driving means.

Figure 4 is a cross sectional view of speed

changing mechanism for the driving means.

Figure 5 is an elevational view looking at the right of Figure 4.

Figure 6 is a plan view of the means to feed the receptacles and position the same upon a receptacle supporting table relative to the closure applying devices.

Figure 7 is a fragmentary detail view to show the mounting of the closure applying devices and the means to maintain the same in operative connection with the actuating cam.

Figure 8 is an elevational view, partly in section, of the means shown in Figure 7.

Figure 9 is a plan view, partly in section, of a separator or interrupter to time and control the feeding of the receptacles to the receptacle supporting table.

Figure 10 is a front elevation of a closure applying device constructed in accordance with my invention.

Figure 11 is a longitudinal sectional view taken substantially centrally of Figure 12 and looking at the right thereof.

Figure 12 is a plan view to show in a diagrammatic manner the relation of the closure supporting means of the respective closure applying devices and the means to feed and seat a closure upon said closure supporting means.

Figure 13 is a side elevation of the means to feed a closure to the closure applying devices and showing the same in relation to said devices when feeding a closure thereto.

Figure 14 is a sectional side elevation of the actuating cam for the closure applying devices to show the construction and arrangement of the movable portion of the cam and the means to permit the yielding movement to said cam portion when a predetermined force is applied thereto to compensate for different sizes of receptacles.

Figure 15 is an elevational view of the mounting of the movable cam portion looking at the right of Figure 10.

Figure 16 is a sectional view taken substantially on the line 16-16 of Figure 15.

Figure 17 is a perspective view of the movable cam portion; and

Figure 18 is a perspective view of the closure supporting means of the closure applying devices.

Similar characters of reference designate like parts throughout the different views of the drawings.

The embodiment of my invention shown in the drawings comprises a base 19 having a standard 20 mounted thereon with an annular table 21 fixed to the upper end of the standard, a vertical shaft or pillar 22 being mounted in the standard to rest upon the base and secured against axial and rotative movement by set screws 23. A receptacle supporting table 24 is rotatably mounted on the standard 20 concentric with the shaft 22

by means of an annular ball race 25, the upper surface of the table being flush with the top of table 21 and having an annular insert 26 of yielding friction material, such as rubber, to constitute the support for the receptacles, such as bottles 27, and serve as a cushion for the receptacle as the closure is being applied thereto.

A carrier or head 28 for the closure applying devices is rotatably mounted upon the shaft 22 and to have longitudinal adjustment thereon, said head being coupled to the table 24 whereby the head and table will be rotated concomitantly and the head may have adjustment on the shaft relative to the table. For this purpose a sleeve 29 mounted upon the shaft is fixed to the table to project upward therefrom, said sleeve having a series of circularly disposed bores 30 for the slidable engagement of rods 30' fixed in and projecting from the lower end of the head 28, said head being maintained in adjusted position by an abutment 31 mounted on the sleeve 29 and abutting against the lower end of the head, said abutment being adapted to have longitudinal adjustment on the sleeve 29 by a key 31^a fixed in a keyway in such abutment by a screw 31^b and slidably engaging a keyway in the sleeve 29, the abutment being secured in adjusted position by a clamping screw 31^c cooperating with the key 31^a to clamp the same and thereby the abutment to the sleeve 29. The head 28 is arranged with a series of circularly disposed slideways 32 of angular shape in cross section with the outer side open, said slideways in the present instance being six in number. To permit of the ready machining of such slideways the upper member 28' of the head is made separate from the member 28 and the two bolted together.

The devices for applying the closures, such as the crown and crimped closures known as "crown caps" are carried by slides or casings 33 of hollow rectangular shape in cross section (Figures 10 and 11) slidably engaging in the slideways and retained therein by removable plates 34 (Figures 7 and 8). Secured to a circular portion at the lower end of each of the casings is a head 35 (Figures 10, 11 and 18) constructed and arranged to provide a space between the end of said head and the casing and having an opening 36 the walls of which flare outwardly to serve as a guiding throat for the passage of the open end of a receptacle such as the neck of a bottle to which a closure is to be applied. This head is also provided with a lateral segmental portion 37 having a guide slot 38 with an opening 39 therein communicating with the space between the head 35 (Figure 18) and the end of the casing (Figure 11). A seat to support a closure in relation to the opening in the throatpiece

is arranged in the space between the head and casing consisting of a plate 40 secured by screws to the head within the recess, said plate having an opening substantially 5 of the same diameter as the opening 36 in the head 35 and having an undercut portion forming a ledge 41 (Figure 12) and the upper surface of the portion opposite said ledge being flush with the lower wall of the opening 39, the rear wall of the ledge 41 serving as a stop to limit the movement of a closure or cap delivered to said seat in a manner to be hereinafter described. An annular sealing die 42 is seated in a recess in the end of 10 the casing in interposed relation to the said plate 40 and the end of the casing with the opening in the die concentric with the openings in the plate and throat, the wall of the opening in said die slightly flaring outward 15 toward the throat opening 36. A plunger 43 is slidably mounted at one end in the end of the casing concentric with the end of the sealing die to have a limited outward movement in said opening and the die, and at the 20 opposite end is mounted in a bushing 44 carried in a closure 45 at the end of the casing opposite to the head 35, said plunger normally being yieldingly urged outward in a direction toward the head 35 by a spring 25 46 with a shoulder 47 thereon in engagement with the end of the casing to limit such outward movement of the plunger, the spring being confined between said shoulder and the bushing 44. The bushing 44 is adjustable 30 in the closure 45 by a set screw 47' whereby to increase or decrease the tension of the spring 46.

As stated the casings carrying the closure applying devices are circularly disposed around the head 28 to have revolving movement around the shaft 22 in superposed relation to the table 24, and to impart reciprocal movement to said casing or slides to move the same toward and away from closure applying position relative to a receptacle, as shown in Figure 1 a cam 48 (Figures 1, 2 and 14) is mounted on the shaft 22 superposed to the slide carrying head and held against rotation by a key 49, this cam being in the nature of a crown shaped cam. The slides or casings are maintained in position with cam following rollers 50 carried by arms 51 integral with the closure caps 45 of the casings, by counterbalancing springs 52 and counterweights 55. One end of the springs engage in recesses 53 (Figure 1) in the head section 28 and pins 54 fixed in laterally projecting lugs of the casings engage in the opposite ends of the springs. The counterweights 55 are mounted in openings 56 in the head section 28 alternating with the slideways 32 (Figures 7 and 8) and connected to the slides by cables 57 passing over grooved rollers 58 mounted on pins 59 extending transversely of the openings and

grooved rollers 60 rotatably supported in a recessed portion at the top of the wall between the slideways and the openings for these weights.

The cam 48 is mounted on the shaft 22 70 against rotation and whereby it will not participate in the rotative movement of the head or carrier for the slides or casings carrying the closure applying devices, and to permit of said cam participating in the longitudinal adjustment of the head 28 on shaft 22, to accommodate the apparatus to the applying of closures to receptacles of different sizes, to maintain the operative relation between the closure applying devices and the cam, the cam is connected to said devices by segmental members 61 fixed to the cam engaging in an annular groove in the head section 28' (Figures 1 and 14). To 75 adjust the connected cam and closure applying devices carrying head upon the shaft the abutment 31 is adjusted on the table sleeve 29 and the head and cam then adjusted as an integral unit by the rotation of a lead screw 62 rotatably carried by a bracket 63 80 mounted in fixed position upon the end of the shaft 22, said screw having threaded connection with the cam to rotate on an axis parallel with the axis of the shaft 22, said lead screw being rotated by a crank applied to a shaft 64 geared to the lead screw as shown at 65 (Figure 2). When the cam and head have been adjusted to the desired position they are locked in said position by 85 screw 31' threaded into the head and impinged upon the key firmly clamping the table to the sleeve.

To rotate or revolve the closure applying devices upon the shaft 22 and about the cam 48 the head carrying said devices is provided with a gear 66, or such teeth of the gear may be cut direct on the head of section 28', meshing with a pinion 67 on shaft 68 mounted in the cam to rotate on an axis parallel with the shaft 22 and to participate in the adjustment of the cam on said shaft, the shaft 68 being held against longitudinal movement relative to the gear 66 by a bevelled pinion 69 fixed to said shaft meshing with a bevelled pinion 70 on a shaft 71 rotatable on an axis 110 transverse to the axis of the shaft 68 for a purpose to be hereinafter described, and which latter shaft participates in the adjustment of the gear 66. The shaft 68 is driven in a suitable manner and as shown may be driven by an electric motor M or by means of a pulley P (Figures 2 and 3) connected to a source of power by a belt (not shown). The shaft 68 is also mounted to have rotative movement and axial adjustment in a bearing 115 72 in the bracket 63.

The driving mechanism (Figures 1 to 5) consists of a driving shaft 73 upon which the pulley P is fixed and to which the motor may be operatively connected by a gear 74 130

on said shaft meshing with a pinion 75 on the shaft of the motor and said shaft 73 being operatively connected to a driven shaft 76 journaled in the bracket 63 geared to the 5 shaft 68 by a bevelled pinion 77 meshing with a bevelled gear 78 rotatably carried by a yoke 79 fixed upon the bracket 63 engaging in an annular groove 80 in the hub of said gear, and mounted on the shaft 68 to rotate 10 with said shaft and permit of axial movement of the shaft relative to said gear by a key 81 engaging in a keyway in said shaft 68.

As stated it is an object of the invention to provide driving means to revolve or rotate 15 the closure applying devices at variable speeds, and for this purpose variable speed gearing is interposed between the driving and driven shaft 73, 76 respectively, comprising an elongated gear 82 fixed on the shaft 73 and an intermediate shaft 83 journaled in casing 86' fixed upon the bracket 63, said shaft having a pinion 84 fixed thereon to mesh with a gear 85' loose on the shaft 76. The intermediate shaft 83 carries gears 20 of variable size thereon, shown as three in number 84, 85 and 86, either one of which is adapted to be operatively connected to gear 82 to connect the driving and driven shafts by pinions 87 carried by levers 88 25 hung on the intermediate shaft 83. An adjustable support is provided for these levers to maintain all of the levers in position with the pinions carried thereby out of mesh with their co-operating pinions 84, 85 and 86 and 30 the gear 82, and permit of the adjusting of one of the levers to cause the pinion carried thereby to mesh with its co-operating intermediate pinion and the gear 82 while maintaining the other levers in position with the 35 pinions carried thereby out of mesh with the gear 82 and their co-operating intermediate pinions. This means comprises a gauge plate 89 slidably mounted upon the casing 86' having a series of slots 90 one for 40 each of the levers. This plate may be adjusted longitudinally as shown in Figure 5 with all of the levers engaging the upper edge of the plate and the pinions carried thereby in idle position, or the plate may be 45 adjusted longitudinally so that one of the levers engages a slot 90, the slots being so located in the plate that when a lever engages in a slot the other levers will be out of line with their co-operating slots and engage on 50 top of the plate. The plate 89 is adjusted by a lever 86'' pivotally mounted upon the casing 86' having a bifurcated end in which a pin 89' projecting laterally from the plate 89 and through an opening 90' in the casing 55 engages. The pinion carrying levers 88 are locked in position when engaging in a plate slot 90 by latches 91, there being one latch provided for each lever as clearly shown in Figure 5. The movement of the pinion 60 84' is transmitted to the gear 85' fixed, as

at 92, to one member of a clutch the other member of which is fixed to the shaft 76, said clutch being shown in a general way at B, and operative by a lever 93 to couple and uncouple the gear 85' to the shaft 76 and thereby connect and disconnect the driving and driven shafts. The driving means are carried upon the bracket 63 mounted in fixed position upon the shaft 22 and by the arrangement of the driving connection of the 75 pinion shaft 68 carried by the cam and the bevelled gear 78 mounted thereon meshing with the pinion 77 on the driven shaft 76 the cam with the closure applying devices may be adjusted longitudinally on the shaft 80 22 without disturbing or breaking the driving connection between said devices and the driving means.

To feed closures to the closure applying devices a closure carrying hopper H is provided (Figure 1) supported by a bracket 94 fixed to the cam and by which the shaft 71 is rotatably supported, the closures being delivered from the hopper to an outlet chute C leading therefrom by a selector in the form of a wheel 95 engaging in an open side of the hopper and fixed to a shaft 96 rotatably supported by the hopper and driven from the shaft 71 by a belt 97 passing around a sheave 98 on the latter shaft and a 95 sheave 99 on the selector shaft 96. The hopper chute is positioned with the outlet to engage in the groove 38 of a segmental portion 37 of a head 35 of a closure applying device carried by a slide or casing 33 100 when the latter are in their fully receded position as shown in Figures 1, 12 and 13, the outlet of the chute being normally shut off by the wall of the groove leading to a closure seat and as an opening in the wall 105 of the groove is brought into register with the chute outlet during the rotative movement of the closure applying devices a closure from the chute will enter to the closure seat, the succeeding closure in the chute being prevented from being delivered from the chute by the wall of the groove being brought opposite to the chute outlet. As a closure is delivered to its seat the succeeding closure in the chute will be in contact therewith and as the closure applying devices move away from the chute outlet there is a possibility that such succeeding closure will 110 impart a rolling movement to the closure engaging the plate 40 and partially unseat the same. To prevent this and cause the closure to seat relative to the plate 40 a finger 100 (Figures 12 and 13) is pivotally supported at one end in a cut out portion of the side wall of the chute at the outlet end, 115 as shown at 101, and yieldingly urged in a direction into the chute by a spring 102, and as the closure applying devices pass such finger a closure which has not been seated 120 relative to the plate 40 will be yieldingly 125 urged into the seat. The closure applying devices 130

engaged by said finger which will tend to force the closure to the ledge 41 but without sufficient force to distort the closure. To positively seat the closure relative to the plate 40 a rigid finger 103 is adjustably carried by a post 104 (Figure 12) fixed in the table 21, the end of this finger being curved, as shown at 105, and normally engaging with the bottom of the groove 38 and as the closure applying devices pass said finger it will engage a closure delivered from the chute to the plate 40 and positively seat the same relative thereto and in position to engage over the opening in the receptacle on the table 24 when the closure applying device is moved to closure applying position by the cam 48. To remove closures which may have been lodged in the chute a portion of the wall of the chute, as 106, (Figures 1 and 13) is releasable, said section of the chute wall being pivotally supported as at 107, and releasably retained in position contiguous to the side walls of the chute by latches 108 pivotally supported at opposite sides of the chute connected by a bar 109 rotatably mounted by lugs 110 on the chute, and said latches retained in position to engage pins projecting laterally from the movable chute section by springs 111. It will be noted that the closure carrying hopper is supported by the cam with the outlet chute in fixed relation to the closure applying devices and will participate in the adjustment of the cam and closure applying devices upon the shaft without disturbing of the closure feeding means relative to the closure applying devices during such adjustment, and without disturbing the driving connection between the closure selecting means of the hopper and the driving means.

To position the receptacles on the table 24 relative to the closure applying devices a wheel 112 is fixed concentrically to the table 24 to rotate therewith (Figure 6) with curved peripheral recesses 113 arranged concentric with the closure applying devices. The receptacles or bottles are delivered to the table 24 positioned in the peripheral recesses 113 of the wheel 112 from a turn table or disk 114, the receptacles being delivered to said disk by hand or by mechanical means from a bottle filling machine (not shown). The receptacles are guided in their travel on the disk 114 in a passageway formed between an upstanding strip 115 mounted upon the fixed table 21 and a strip 116 mounted on a plate 117 fixed to the table 21, said strips being adjustable relative to each other to provide passageways of different widths for different sizes of receptacles. The disk 114 is rotatably supported with a peripheral portion to overlap a peripheral portion of the table 24 in the rotation thereof, as clearly shown in Figure 6, and is rotated by a gear 118 rotatable with the table

24 meshing with a gear (indicated by dot and dash line 119) fixed to the disk 114 to rotate the disk in the direction indicated by the arrow. It will be noted that the leading walls of the recesses in the wheel 112 are sloped in the direction of rotation of the wheel while the following wheel portions of the recesses are concaved inwardly. By this arrangement of the recesses the receptacles will readily enter the recesses from the disk 114 and will be positively engaged by the following wall portions of the recesses whereby the receptacles are caused to positively move with the table 24.

To time the delivery of the receptacles from the disk to the table 24 in proper timed sequence to the positioning of the wheel recess 113 opposite to the outlet of the passageway between the strips 115, 116 means are provided comprising an arm 120 pivotally supported at 121 and having a longitudinally adjustable portion 120' (Figure 9) carrying a finger extending at a right angle to the arm in the form of a slidably supported pin 122 normally urged in outward direction by a spring 123 and adapted to project into the path of travel of the receptacles on the disk as clearly shown in Figure 6, said arm carrying a roller 124 to engage a wheel 125 concentric and rotatable with the disk arranged with a series of circumferential cam portions equal in number to the recesses in the wheel 112, said arm 120 being normally yieldingly urged to position by a spring 126 with the roller 124 in engagement with the cam wheel 125. The roller 124 is carried upon a stud 124' mounted in a slot 125' of arm 120 whereby the arm may be positioned so that the pin 122 will be projected into the path of movement of the receptacle in the delivery thereof to the table 24 to a greater or less extent and compensate for different sizes of receptacles. The cam wheel 125 is so positioned relative to the positioning wheel 112 that after a receptacle has been delivered from the disk and positioned into a recess of said wheel the finger 122 will be projected into the path of movement of the receptacles on the disk separating and interrupting the travel of the receptacles with the disk, and will be moved out of position in said passageway when a recess in the wheel 112 comes opposite the outlet of the passageway and permit the delivery of a receptacle from the disk to such recess. By the adjustment of the finger carrying portion 120' of the arm the separating and interrupting means is adapted for different sizes of receptacles. To maintain the receptacles on the table 24 in position within the wheel recesses 113 guides 127 and 128 are provided, the guide 127 being laterally adjustable for different sizes of receptacles, and the guide 128 is supported to have movement in a

radial direction toward and away from the wheel 112 by a pair of studs 129 supporting said guide slidably mounted in a bracket 130 adjustably mounted on the table 21 and 5 yieldingly urged in a direction to engage receptacles on the table 24 by springs 131 to maintain the receptacles in the wheel recesses 113. The receptacles are delivered from the table 24 to the passageway formed 10 by a pair of strips 146 mounted on the table 21 to have adjustment relative to each other to provide a passageway of different widths from which the receptacles may be removed 15 by hand or delivered to suitable transferring means (not shown).

The receptacles, such as glass bottles, to which the apparatus is particularly adapted to apply closures are invariably of different sizes or heights and as the mechanism is 20 arranged to impart a predetermined closure applying movement to the closure applying devices carrying slides in applying a closure to a receptacle, should a receptacle of greater height than the space between the table 24 and the closure applying devices for 25 which the latter was adjusted a crushing force or pressure will be applied to the receptacles and the consequent breakage of the same. To prevent the breakage of receptacles in this manner means are provided 30 to permit of movement of the closure applying devices relative to the table when a pressure greater than a predetermined force is applied to such devices to compensate 35 for the inequality in the sizes of the receptacles. For this purpose the portion of the cam constituting the working or high portion of the cam, as shown at 48' in Figures 14, 15 and 16, is adapted to have trans- 40 verse movement of the body of the cam when pressure greater than a predetermined force is applied thereto. This portion 48' of the cam is slidably mounted and is normally urged in a downwardly direction by a spring 133 with lugs 134 arranged on said cam portion engaging with the cam proper and the working face of such cam portion flush with the working portion of the cam proper as clearly shown in Figure 15. This 45 spring normally maintains the cam in this position. However, to maintain said cam portion in such position to be released when a pressure greater than a predetermined force is applied thereto a roller 135 is rotatably carried by a pair of arms 136 extending upward from said cam portion to engage with a curved or cam portion 137 of a lever or arm 138 pivotally supported at 139 on a bracket 140 mounted on the cam proper 50 out of line or at one side of the plan of movement of the cam portion 48' to take up end thrust of said cam portion. The curved end of this lever is arranged with a portion to extend down in front of the roller, said lever being yieldingly urged 55

rearward with said extending portion of the curved end to engage the roller by a spring 141 carried by a transverse yoke 142 of the bracket 140, said spring being confined between the lever or arm 138 and an adjustable abutment 143 to increase and decrease the tension of the spring. When a pressure greater than the predetermined force is applied to the cam from the cam portion 48' by the closure applying devices, which 70 pressure is regulated by the spring 141, such cam portion will be moved against the tension of the spring 133, and the roller 135 forced against the curved end of the lever 135 moving the lever laterally against 75 the tension of the spring 141 and permitting upward movement of the cam section 48'. As soon as the cam section 48' is relieved of the excess pressure of the closure applying devices such cam portion will be returned to initial position by the spring 133 and the pressure of the spring 141 on the lever or arm 138. The tension of the springs 133 and 141 is such as to exert 80 sufficient resistance to the cam portion 48' as to cause the closure applying devices to perform their closure applying function. A protecting shield 145 is mounted upon 85 the cam to extend around the same.

To provide lubricant between the head 28 and the shaft 22 a bore or passage 146 is drilled into the upper end of the shaft having lateral outlets 147 to the contacting surface between said shaft and head, a lubricant carrying cup 148 being in communication with said bore through a tubular stem 149 supported in an enlargement of the bore at the end of the shaft. 90

Having thus described my invention I 105 claim:

1. In apparatus for applying closures to receptacles, the combination of a fixed shaft; a rotatable receptacle supporting table concentric with said shaft; closure applying devices rotatably mounted on the 110 shaft and to have longitudinal reciprocable movement and adapted to have longitudinal adjustment on the shaft relative to the table; means to couple the closure applying devices with the table to rotate therewith and permit of adjustment of said devices relative to the table and maintain the driving connection between the same; a cam mounted on the shaft and connected to the closure applying devices to participate in the longitudinal adjustment thereof, and with which cam said devices co-operate to impart the closure applying movement thereto, driving means supported upon the 115 shaft in fixed position and operatively connected to the closure applying devices; a lead screw carried by the support for the driving means having threaded connection with the cam; and means to rotate said lead screw to adjust the cam with the connected 120 125 130

closure applying devices on the shaft for the purpose specified.

2. In apparatus for applying crown closures to receptacles, the combination of a fixed shaft; a table rotatably supported concentric with said shaft; reciprocable closure applying devices rotatably mounted on the shaft and to have longitudinal adjustment toward and away from the table; a cam on the shaft to participate in the longitudinal adjustment with said devices, and with which the devices co-operate to be moved to closure applying position; a closure carrying hopper mounted on the cam and participating in the adjustment of said cam and closure applying devices, said hopper having an outlet chute arranged to deliver closures to the closure applying devices; driving means for the closure applying devices supported in fixed position on the shaft; and means to operatively connect said driving means to the closure applying devices comprising a shaft rotatably mounted in the cam, a pinion on said shaft, a gear meshing with said pinion connected to the closure applying devices, said rotatable shaft being adapted to participate in the adjustment of said cam and closure applying devices on the fixed shaft, and gearing to connect said rotatable shaft with the driving means including a gear rotatable with the rotatable shaft and relative to which gear said latter shaft is axially movable.

3. In apparatus for applying crown closures to receptacles, the combination of a fixed shaft; a table rotatably supported concentric with said shaft; reciprocable closure applying devices rotatably mounted on the shaft and to have longitudinal adjustment toward and away from the table; a cam on the shaft to participate in the longitudinal adjustment with said devices, and with

which the devices co-operate to be moved to closure applying position; a closure carrying hopper mounted on the cam to participate in the adjustment of said cam, said hopper having an outlet chute to deliver closures to the closure applying devices and a selector to deliver closures from the hopper to the chute; driving means for the closure applying devices and the selector of the hopper supported in fixed position on the shaft superposed to the closure applying devices; and means to operatively connect said driving means to the closure applying devices; comprising a shaft rotatably mounted in the cam, a pinion on said shaft, a gear meshing with said pinion connected to the closure applying devices, said rotatable shaft participating in the adjustment of said cam and closure applying devices on the fixed shaft, gearing to connect the rotatable shaft with the driving means including a gear rotatable with the rotatable shaft and relative to which gear the rotatable shaft is axially movable, and means to operatively connect the closure selector of the hopper with the rotary shaft.

4. In apparatus for applying crown closures to receptacles, the combination of a fixed shaft; a receptacle supporting table concentric with the shaft; a cam mounted on the shaft; a head rotatably mounted on the shaft in juxtaposed relation to the cam arranged with circumferentially disposed slideways, and openings alternating with the slideways; closure applying devices slidably mounted in the slideways; and counterweights connected to the closure applying devices engaging in the openings alternating with the slideways to maintain said devices in position with the cam rollers in engagement with the cam.

ARON JOHNSON.
